UNITED STATES PATENT OFFICE.

WALTER H. WAKEFIELD, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

YARN-IMPINGING LAY-ACTUATED WEFT DETECTOR CONTROLLED BY BOX MOTION.

Application filed December 30, 1924. Serial No 758,905.

This invention relates to improvements in weft detectors for use with multi-box looms employing a plurality of shuttles any one of which may become active and the principal object of the invention is to provide means for rendering the detector more sensitive when detecting one character of yarn than when detecting another character of yarn.

It is a more particular object of my invention to render a detector having a yarn impinging member and a lay actuated member variably sensitive depending upon which shuttle is active.

It is a further object of my invention to provide a detector of this type wherein all of the detector parts proper retain their same adjustment and wherein the variable portion of the mechanism is carried by the lay.

With these and other objects in view which will appear as the description proceeds, my invention resides in the combination and arrangement of parts hereinafter described and set forth in the claims.

In the accompanying drawings wherein I have shown one embodiment of my invention,

Fig. 1 is a front elevation of a portion of a loom having my invention applied thereto and showing the same as provided with shuttle boxes to accommodate two shuttles,

Fig. 2 is a top plan view of the detector, certain parts being in section,

Fig. 3 is a vertical section on line 3—3 of Fig. 2,

Fig. 4 is a vertical section on line 4—4 of Fig. 3 and showing the method of mounting the slide on the lay which renders the detector variably sensitive, and

Fig. 5 is an enlarged section on line 5—5 of Fig. 1.

Referring to the drawings it will be seen that I have provided a loom frame 10 and a lay 11 on which is mounted for vertical motion a plurality of shuttle boxes 12 which may be actuated in any approved manner by mechanism not shown forming no part of the present invention. Said shuttle boxes have a frame 13 on which is mounted a plurality of binders 14, said binders terminating a sufficient distance from the inner end of the frame 13 to permit the latter to have secured thereto a block 15 having formed therewith a groove 16.

The lay end 17 may be secured in any approved manner to the lay and has a horizontal shelf 18 to which is secured a stand 19 from which projects a stud 20. Pivotaly mounted on said stud is a vertical lever 21 the upper end of which is provided with a stud 22 which runs in groove 16 causing said lever to assume different angular positions depending upon the position of the offset in said groove. As shown herein said groove or slot is provided with an offset corresponding to the second shuttle box which is shown in active position. The lower end of said lever 21 is adjustably connected by means of link 23 to a second lever 24 located on the opposite side of the loom and pivotally mounted on a stud 25 which extends from a stand 26 depending from the lay 11. The upper end of the lever 24 is slotted as at 27 and has driving connection with a slide block 28 by means of a connecting stud 29 shown in Fig. 1. The block 28 is slidably mounted in a guide 30 having a foot 31 extending under and secured to the box plate 32 and affording means whereby said guide may be supported to the box frame. A cap 33 retains the block in the guide.

The block 28 is provided with actuating surfaces of different heights, the form of block shown herein having a low surface 34 and two high surfaces 35 which are in effect the front face of said block. As the shuttle boxes 12 are raised and lowered the lever 21 will be given a motion depending upon which shuttle is active, the offset 36 in the slot 16 and the low surface 34 in the slide block 28 corresponding to a shuttle having fine yarn.

The detector is located on the opposite side of the loom from the boxes 12 and comprises a stand 40 secured in any approved manner to the loom frame 10 and having upstanding therefrom a horn 41 through which projects a controller pin 42 normally lying across a slot 43 in said horn to be under the path of a regularly reciprocated actuating lever 44. When sufficient yarn for continued weaving is present, said controller, which is normally under the lever 44, will be withdrawn sufficiently to allow said lever 44 to descend without being interrupted, but when an indication of weft exhaustion is to be given the controller pin 42 will remain

under said lever and cause the opposite end thereof (not shown) to descend to give an indication to the weft replenishing mechanism. This portion of the mechanism is old and may be the same as shown in Patent No. 1,030,748 to which reference may be had for further description and illustration of the same.

The controller 42 is pivotally connected 10 to the upper end of an arm 45 the lower end of which is secured in adjusted position to a shaft 46 which turns freely in a pair of bearings 47 and 48, respectively, extending forwardly from the frame 40. A second 15 arm 49 is secured in angularly adjusted position to said shaft 46 and is normally held rearwardly by a torsion spring 50 one end of which is connected to a collar 51 secured to the shaft 46 and the other end of which 20 is received by bearing 48. The spring 50 also serves to hold the controller 42 under the actuator lever 44.

A feeler bed 52 is mounted on a threaded sleeve 53 supported by the frame 40 and has 25 slidably mounted therein a detector slide 54. A clip 55 secured to the slide 54 extends upwardly therefrom and has extending therethrough a stud 56 the rear end of which is enlarged and threaded as at 57 to 30 serve as a stop for said clip and slide, a spring 58 surrounding said stud 56 and pressing against the forward end of a cap 59 to hold said slide normally in rear position. That portion of the detector so far 35 described may be the same as that set forth in Patent No. 972,722.

In carrying my invention into effect I provide a yarn impinging detecting element 60 pivoted as at 61 to the slide 54 and having 40 the rear portion thereof provided with teeth 62 which are so proportioned as to be embedded in the yarn when a bobbin supplied with sufficient yarn is presented thereto. A rod 63 has an enlarged forward end 45 64 to receive a stop screw 65 the rear end of which is positioned to engage the bed 52. The rear end of said rod 63 is hook shaped as at 66 to extend around the laterally projecting arm 67 of the yarn impinging detector 60. Said rod 66 has a bearing block 68 secured thereto through which extends the rear end of a push rod 69, and the forward end of said push rod passes through a block 70 rigidly secured to the slide 54 and engages lever 49.

In operation when there is a sufficient supply of working weft for continued weaving the teeth 62 of the detector 60 will be embedded in the yarn so that as the same moves forwardly it will be held against angular motion under influence of spring 50. When the working layer of yarn becomes depleted to such a thickness as to make an indication of exhaustion desirable a screw 65 71 which is adjustably held in a boss 72 de-

pending from the slide 54 will be engaged by the slide block 28 before the teeth 62 engage the yarn and as slide 54 is moved forwardly by the lay the rod 69 will give the detector 60 an angular motion to the left, 70 the controller 42 remaining under lever 44 so that the latter is prevented from having its normal downward motion and indication of weft exhaustion is communicated to the replenishing mechanism. Obviously the 75 thickness of the layer of yarn left on the bobbin will be determined by the time at which the block 28 strikes the screw 71. As shown in the drawings the detector is positioned for fine yarn, the relatively low surface 34 engaging the screw 71 at a comparatively late time in the forward beat of the lay permitting the teeth 62 to be nearer the center of the bobbin when the detector 60 starts to move rearwardly. When the boxes 80 change so that coarse yarn is woven the block 28 will be moved longitudinally to bring one of the relatively high surfaces 85 35 opposite the screw 71 which condition means that the detector 60 will start to move with the bobbin when the same is farther from the teeth 62 than was the case when the fine yarn was being woven. In this way the detector operates in timed relation with the active shuttle to give an amount of waste 90 which is permissible for both sizes of yarn.

The screw or stud 71 is provided with a broad head 73 which engages the slide 28, the head having beveled edges to assist in passing from one to the other of the surfaces 34 and 35.

From the foregoing it will be seen that I have provided a feeler having a yarn impinging surface and actuated by the lay so constructed as to be more sensitive when detecting fine yarn than when detecting coarse yarn. It will be further noted that the mechanism which effects this change is mounted on the lay and the detector parts retain the same relative position so that they may retain the same setting for all degrees of sensitiveness. Also, the slide and its controlling mechanism are located entirely on the lay, the force to move the slide being derived directly from the boxes and conveyed positively to said slide.

Having thus described my invention it will be apparent that changes and modifications may be made therein by those skilled in the art without departing from the spirit and scope of the invention and I do not wish to be limited to the details herein disclosed, but what I claim is:

1. In a loom having a plurality of shuttle boxes each of which is movable to active position, a lay, shuttles for the boxes having a weft supply to be detected, a detector having a yarn impinging member and a lay actuated member, and means under control of the shuttle boxes and dependent upon which 125

box is in active position to determine the time of actuation of the said member actuated by the lay.

2. In a loom having a plurality of shuttle boxes each of which is movable to active position, a lay, shuttles for the boxes having a weft supply to be detected, a weft detector having yarn impinging and lay actuated members movable with the detector, and means operating in timed relation with the shuttle boxes and dependent upon which box is in active position to determine the time of actuation of said lay actuated member.

3. In a loom having a plurality of shuttle boxes each of which is movable to active position, a lay, shuttles for the boxes having a weft supply to be detected, a yarn impinging detector, a lay actuated member operatively associated therewith, and means under control of the shuttle boxes and dependent upon which box is in active position to vary the time of actuation of said member on the forward beat of the lay.

4. In a loom having a plurality of shuttle boxes any one of which may become active, a weft detector having a yarn impinging member and a lay engaged member, and means under control of the active shuttle box to vary the distance intervening between the yarn engaging surface of the yarn impinging member and the surface of the lay engaged member which is engaged by the lay.

5. In a loom having a plurality of shifting shuttle boxes any one of which may become active, a lay, a yarn impinging detector, an actuator operatively connected to the detector, and a member on the lay movable under control of the active shuttle box and positioned to engage the actuator at different times in the forward movement of the lay.

6. In a loom having a plurality of shifting shuttle boxes each of which may become

active, a yarn impinging detector, means to render said detector effective to give an indication of substantial weft exhaustion when the distance between said detector and the bobbin reaches a predetermined amount, and means under control of the active shuttle box to vary the predetermined amount of distance between said detector and the bobbin necessary to render said detector operative to indicate weft exhaustion.

7. In a loom having a plurality of shifting shuttle boxes each of which may become active, a yarn impinging detector, a lay, means to render said detector effective to give an indication of substantial weft exhaustion when the distance between said detector and the bobbin reaches a predetermined amount, and means under control of the active shuttle box to vary the predetermined amount of distance between said detector and the bobbin necessary to render said detector operative to indicate weft exhaustion, said means including a member engaging a part of the lay.

8. In a loom having a plurality of shifting shuttle boxes each of which may become active, a weft detector having a yarn contacting element and a lay engaged actuator, mechanism to indicate weft exhaustion, said mechanism remaining inoperative so long as the yarn contacting element engages the yarn before the lay engages the actuator and becoming operative when the lay engages the actuator before the contacting element engages the yarn, and means under control of the active shuttle box and dependent upon which shuttle box is active to vary the time of engagement of the actuator by the lay as the latter moves toward the detector.

In testimony whereof I have hereunto affixed my signature.

WALTER H. WAKEFIELD.
